UNITED STATES PATENT OFFICE.

EDMUND A. SCHADE, OF NEW BRITAIN, CONNECTICUT, ASSIGNOR TO THE STANLEY RULE & LEVEL COMPANY, OF NEW BRITAIN, CONNECTICUT, A CORPORATION OF CONNECTICUT.

ROOF-BRACKET.

1,172,227.

Specification of Letters Patent. Patented Feb. 15, 1916.

Application filed March 2, 1915. Serial No. 11,475.

To all whom it may concern:

Be it known that I, EDMUND A. SCHADE, a citizen of the United States, residing at New Britain, county of Hartford, State of Connecticut, have invented certain new and useful Improvements in Roof-Brackets, of which the following is a full, clear, and exact description.

This invention is concerned with an improved form of bracket for supporting boards, shelving or platforms upon slanting roofs, thereby being instrumental in forming a staging on the roof, this staging being used by the workmen in building or repairing as well as a support for other purposes.

Preferable embodiments of my improvement are illustrated in the accompanying drawings, in which,—

20 Figure 1 is a perspective view of a preferred form of my bracket in position on a roof. Fig. 2 is a longitudinal vertical section through the bracket shown in Fig. 1. Fig. 3 is a fragmentary perspective view of 25 the bracket. Fig. 4 is a horizontal section on the line 4—4, Fig. 2. Fig. 5 is a fragmentary perspective view of a modified form of bracket.

Referring to the drawings in detail, A 30 designates a roof and B shingles thereon, the bracket of the present invention being particularly adapted for use in connection with shingled roofs. The bracket of the present invention has an outer and inner frame. The outer frame is in the form of a substantially V-shaped member, preferably of light metal strip stock, one arm 1 being substantially horizontal and forming the load supporting portion, the other arm 40 2 providing a supporting standard therefor which is arranged to extend substantially vertically. The inner end of the arm 1 is up-turned at 3, forming in normal position an obtuse angle with the horizontal strip, as shown in dotted lines in Fig. 2. This up-turned foot 3 is of a pliant material which will permit it to bend somewhat under pressure and is intended for insertion beneath the lower edge of a shingle. The lower end of the arm 2 of the bracket frame 45 is cut away to provide gripping points or edges 4—4 for engagement with the face of a shingle. The inner frame is somewhat rectangular in shape and comprises a foot portion 5 forming one side, an end 6 rigidly

secured to the arm 2 of the outer frame, and a vertically extending side 7 with a down-turned end 8 cut away to provide gripping points 9. The arm 7 and the end 8 are not attached to the outer frame and 60 the gripping points are located inwardly of the foot portion 5 a sufficient distance to permit a shingle to be inserted therebetween, the end 8 and arm 7 yielding under pressure to provide for variation in the 65 thickness of the shingles. The feet portions 3 and 5 in their normal positions are in parallel planes and are each adapted to be inserted beneath a roof shingle. They extend however at such an angle relative to 70 the main body of the frames that when they are so inserted beneath the lower ends of adjacent shingles, as indicated in Fig. 2, the foot portion will be bent outwardly, the material of the frame so permitting, and 75 this action will tend to force the gripping points 4 into the shingle so that the bracket may not be accidentally displaced, the load subsequently placed upon the member 1 of 80 the bracket exerting further gripping pressure upon the gripping points or prongs 4 and 9, as will be later seen. This bending of the feet portions 3 and 5 therefore serves to force the gripping points 4 at the lower 85 end of the bracket structure into the wood of the shingle.

In using these brackets a plurality are applied to the shingles of the roof as described and a platform or other staging C is laid across the load supporting members of 90 the brackets, the weight of this platform pressing the gripping points 4 and also the gripping points 9 firmly into their respective shingles, or into the roofing, as the case may be. The load strain tends to cause the members 2 and 7 to buckle outwardly. This is particularly true if the bar forming the platform is made of sufficiently light stock to permit the feet to bend under practical 95 working conditions. I find, however, that by strengthening these portions against buckling, such a grade of stock may be employed to give the desired results without weakening the bracket and making it liable to buckle under load strain. I preferably 100 so strengthen the arms or members 2 and 7 by forming the same with corrugations 10 and 11 respectively, which are inwardly directed and which therefore will strengthen 105 their respective bars against outward buc- 110

kling. The load supporting portion 1 of the bracket will engage the upper end of the inner frame and exert pressure upon the down-turned end 8 thereof so as to force 5 the prongs 9 into the shingle. This pressure will also tend to buckle the bar 7 outwardly but this is prevented by the use of the strengthening corrugations described.

I have also provided an improved load 10 supporting means including means for retaining the staging or boards on the load supporting bar 1. A preferable embodiment of this feature is shown in Fig. 3 wherein an extra strip or bar 12 is superposed upon the 15 bar 1 of the bracket and is rigidly secured thereto, as by riveting, thus strengthening the bar and tending to prevent it from buckling under load strain. This bar 12 has its ends upturned adjacent the extremities of the frame, one end 13 having an aperture therein through which a nail or other securing device 15 may be driven into the staging C. The other end 14 is upturned 20 at an angle to form a lug substantially parallel with the bent foot 3, the space between 25 these two portions being sufficient to receive the shingle under which the foot 3 is inserted. The lug 14 of the bar is provided with an aperture through which a nail or 30 other securing device may be driven into the inclosed shingle, this nail also acting to prevent the staging C from being accidentally removed from the bracket. The foot 35 3 prevents the nail from penetrating an underlying shingle.

A modified form of load support is shown 40 in Fig. 5, wherein 1^a designates the load supporting bar of the outer frame and 3^a its up-turned foot. I dispense with the superposed bar by forming the bar 1^a with an inwardly directed corrugation 17, thereby 45 strengthening the bar 1^a against inward buckling under load strain. A short strip 18 is rigidly secured to the edge of the

frame and extends upwardly forming a retaining flange for the staging C. Another short strip 19 is rigidly secured to the other end of the frame extending parallel with the bent foot 3^a, and space between these two receiving the shingle and the parts 18 and 19 50 having apertures therein to receive nails or other similar devices, as in the first form described.

The upper face of the upper supporting strip, whatever form of bracket is employed, 55 is preferably provided with spurs or similar retaining means for engaging the under face of the staging or platform C, as indicated in the drawings.

From the foregoing it will be seen that I 60 have devised a simple and efficient form of roofing bracket which however is susceptible of modification both in form and relative arrangement of parts within the scope of the appended claim.

What I claim therefore and desire to secure by Letters Patent is:

A roofing bracket comprising a frame having a substantially horizontal load supporting member, a foot and a substantially parallel lug at one end thereof and extending at an angle oblique thereto, the said lug having a nail hole located above the foot, a supporting standard projecting downwardly from the other end of said load supporting portion and having a lower roof engaging edge, a second supporting standard arranged below said horizontal load supporting portion, and having at its lower end a roof engaging edge, an upwardly directed 80 foot on the first mentioned standard arranged to be projected beneath a roof shingle.

EDMUND A. SCHADE.
